(57) **CLAIM**

The ornamental design for tire, as shown and described.

DESCRIPTION

FIG. 1 is a perspective view of tire showing our new design;

FIG. 2 is a front view thereof;

FIG. 3 is a back view thereof;

FIG. 4 is a left view thereof;

FIG. 5 is a right view thereof;

FIG. 6 is a partially enlarged view of FIG. 2; and,

FIG. 7 is a partially enlarged view of FIG. 4.

The top view and the bottom view are omitted as they are the same with the front view. The broken lines shown on the drawings depict portions of the tires that form no part of the claimed design.
